ELECTRIC CIRCUIT-BREAKER OF THE
GAS-BLAST TYPE

Donald Foster Amer, Newcastle-on-Tyne, England, assignor to A. Reyrolle & Company Limited, Hebburn-on-Tyne, England, a company of Great Britain

Application April 1, 1949, Serial No. 84,904

Claims priority, application Great Britain
April 23, 1948

24 Claims. (Cl. 200—148)

1

This invention relates to electric circuit-breakers of the gas-blast type in which the contacts separate within an arcing enclosure maintained filled with gas under a superatmospheric initial or "filling" pressure, a blast of deionising gas flowing from the enclosure to assist in extinguishing the arc when the circuit-breaker is opened.

If, as in some arrangements, the blast of deionising gas is produced by opening an exhaust valve so that gas from the enclosure flows through a nozzle or vent adjacent to the separating contacts, the initial or filling pressure within the enclosure necessarily commences to fall from the initial value as soon as the exhaust valve opens. In order, therefore, to afford the requisite blast during the separation of the contacts, a high initial pressure is desirable and the enclosure has to be mechanically designed to maintain and withstand such pressure. In conflict with this requirement is the fact that the higher the initial or filling gas pressure the greater the risk of moisture condensation within the circuit-breaker.

The invention has for its object to overcome these and other difficulties.

In a circuit-breaker according to the invention, means are provided whereby the initial or filling gas pressure within the enclosure is supplemented during opening of the circuit-breaker.

The initial gas pressure may be supplemented by supplying to the enclosure gas under a pressure exceeding the initial or filling pressure, or by applying pressure to the gas within the enclosure.

Preferably, the initial or filling gas pressure does not appreciably exceed that necessary for the optimum restriking gap between the open contacts to withstand full voltage, the said initial pressure being supplemented during opening of the circuit-breaker to provide the requisite gas blast. In this way, under normal operating conditions, the contact enclosure only has to withstand and maintain the comparatively low filling pressure whilst, at the same time, adequate gas pressure is available to provide the requisite gas blast without any fall in pressure at the commencement of the contact separation. Moreover, since the gas pressure within the enclosure does not fall below the initial or filling value, the gap between the open contacts can be reduced to a value corresponding to that necessary for effective arc extinction.

The invention may be carried into practice in various ways but four constructions, each embodying the invention, are shown diagrammati-

2

cally, and by way of example, in Figures 1 to 4 respectively of the accompanying drawings, the apparatus being shown in longitudinal section in each figure.

In the embodiment shown in Figure 1, the circuit-breaker comprises a hollow, and externally shedded, post insulator A mounted vertically on, and in open communication with, a metallic base B having incorporated therein or connected thereto a gas supply reservoir B¹ in which a high gas pressure, say 250 pounds per square inch, is maintained. The reservoir B¹ communicates with the interior of the post insulator A through a reducing valve B² by which the gas is expanded and supplied at a pressure lower than that within the reservoir B¹. For example this lower gas pressure, hereinafter referred to as the initial or "filling" pressure, may be of the order of 75 pounds per square inch. The reservoir B¹ communicates with the interior of the base B through a blast valve B³ controlled by an "opening" solenoid S¹, whilst a relief valve B⁴ in the base B is controlled by a "closing" solenoid S², the two solenoids S¹S² constituting parts of a control circuit S for opening and closing the circuit-breaker.

Mounted on top of the post insulator A is a cup-like or upwardly flaring metallic member A¹ constituting the lower portion of a contact enclosure C which is completed by a cylindrical and externally shedded intermediate insulator A² disposed on the said lower portion A¹ and carrying an upper metallic portion or head A³. The lower metallic portion A¹ of the enclosure C is provided with an internal spider A⁴ which supports, in axial alignment with the hollow post insulator A, a rod-like fixed contact C¹ which thus extends axially within the enclosure C. The upper wall or head A³ of the enclosure C has a downwardly extending metallic skirt D furnished at its lower end with a tubular shroud D¹ of insulating material, the skirt D and shroud D¹ thus extending downwards in the annular space between the cylindrical wall of the enclosure C and the fixed contact therein C¹. Formed in the metallic skirt D adjacent to the upper or free end of the fixed contact C¹ is an opening D² through which extends a moving contact C² operated by a piston C³ movable in a cylinder C⁴ extending laterally from the metallic head A³ of the enclosure C, the moving contact C² cooperating with a brush contact C⁶ electrically connected to and lying within the said head A³. The contact piston C³ is provided with a bleed passage C⁵ which establishes open

communication between the enclosure C on one side of the piston C³ and the cylinder C⁴ on the opposite side thereof, for the purpose described below.

Formed in the upper wall of the metallic head A³ so as to be substantially coaxial with the fixed contact C, is a nozzle E flaring upwards into a cooling chamber E¹ whose upper or outlet end has an exhaust port E² controlled by an exhaust valve E³ mounted on a resilient diaphragm E⁴ (e. g. of rubber or springy metal) constituting part of the lower wall of an auxiliary chamber E⁵ in open communication, through a bleed pipe E⁶, with the interior of the contact enclosure C.

With the circuit-breaker in the closed condition, as shown in Figure 1, the moving contact C² extends through the opening D² in the metallic skirt D into engagement with the upper end of the fixed contact C¹, the circuit being thus completed from the lower metallic portion A¹ of the enclosure constituting one pole X of the circuit-breaker, and through the fixed and movable contacts C¹, C² to the upper portion or head A³ constituting the second pole Y.

Both the blast valve B³ and the relief valve B⁴ in the metallic base B are now in their closed positions, but the interior of the enclosure C is maintained filled with gas at an initial or filling pressure of, say, 75 pounds per square inch, from the reservoir B¹ through the reducing valve B². The pressure being equalised, through the bleed passage C⁵ in the contact piston C³, on both sides thereof, the contacts C¹C² remain in the closed position. Further the gas pressure is insufficient to open the exhaust valve E³ and, apart from the gas being comparatively dry due to expansion by traversing the reducing valve B², is sufficiently low to be readily maintained and withstood by the enclosure.

If it is desired to open the circuit-breaker, the opening solenoid S¹ is energised thus opening the blast valve B³ so that the reservoir B¹ is brought into open communication with the interior of the enclosure C. The excess pressure on the inner face of the contact piston C³ thus causes the moving contact C² to be retracted from the fixed contact C¹ thereby drawing an arc transversely within the metallic skirt D. The increased pressure within the enclosure C is transmitted through the bleed pipe E⁶ to the auxiliary chamber E⁵ so that the diaphragm E⁴ is flexed and the exhaust valve E² opened. A blast of deionising gas, at the supplemented pressure, is thus caused to flow through the nozzle E so that the end of the arc rooted on the moving contact C² is transferred first to the adjacent wall of the metallic skirt D and then to, and through, the nozzle E whereby the arc is extinguished. After a predetermined interval, the opening solenoid S¹ is deenergised so that the blast valve B³ is closed and the pressure within the enclosure C returns to the initial or filling pressure, the exhaust valve E³ at the same time returning to the closed position due to the fall in pressure. The pressure being again equalised on opposite sides of the contact piston C³, the movable contact C² remains in its open position.

The initial or filling pressure now obtaining in the enclosure C, whilst inadequate to provide the requisite gas blast during opening of the circuit-breaker, is sufficient to withstand full voltage between the open contacts C¹C² across a gap which does not exceed the optimum for effective extinction by the gas blast produced by the in-

creased pressure during opening of the circuit-breaker. In this respect it will be apparent that the filling gas pressure at the gap is maintained or increased except during the closing operation, now to be described.

In order to close the circuit-breaker, the closing solenoid S² is energised so as to open the relief valve B⁴ in the base B. The sudden pressure drop on the contact side of the contact-piston C³ allows the initial-filling-pressure gas at the back of the piston C³ to cause it to move inwards thereby moving the movable contact C² back through the opening D² in the metallic skirt D and into engagement with the fixed contact C¹. The relief valve B⁴ is then reclosed so that the pressure within the enclosure C is restored to the initial or filling value.

It will be understood that the invention may be applied either to single-break or to multi-break circuit-breakers. Moreover, instead of the contacts being movable laterally with respect to the nozzle as described above, the movement of the contacts may be axial with respect to the nozzle or vent. One such construction is shown in Figure 2, in which the upper end of the hollow post insulator A carries a short intermediate cylindrical metallic member F having an internal spider F¹ which supports a pneumatic cylinder F² containing a vented piston F³ at the lower end of a rod-like movable contact F⁴. The contact enclosure G is completed by a plurality of short coaxial insulating tubes G¹ mounted in axial alignment with, and on top of, the cylindrical metallic member F, each insulating tube G¹ being constituted by two annular rings of insulating material arranged one within the other and radially spaced apart. The annular spaces G² between the insulating rings G¹ are in open communication with each other and, through a passage G³ in the wall of the intermediate cylindrical member F, with the pneumatic cylinder F² on that side of the piston remote from the contact enclosure G.

Thus, for purposes of additional insulation, the supplementary annular space G² in the insulating wall of the built-up contact enclosure G remains in open communication with the dry-gas space represented by the contact enclosure G and pneumatic cylinder F², the gas trapped in this supplementary space also assisting the closing movement of the piston F³ when the pressure within the contact enclosure G is relieved or released to reclose the circuit-breaker as described below. The uppermost tube G¹ is closed by a dome or head plate H¹ having a central internal pin or rod H constituting the fixed contact in axial alignment with the movable contact rod F⁴. The short insulating tubes G¹ are axially spaced apart by a number of metallic rings J each of which has an exhaust pipe J¹ extending radially from within the enclosure G and through the outer wall thereof. The exhaust pipes J¹ are provided with transverse passages or vents J² lying in alignment with the fixed and movable contacts H, F⁴, the outer end of each exhaust pipe J¹ being closed by a spring-loaded exhaust valve J³.

With the circuit-breaker in its closed condition, the interior of the enclosure G is filled with gas at the initial or filling pressure, this filling being maintained from the reservoir B¹ through the reducing valve B² as described above. The movable contact rod F⁴ is now in its uppermost position as shown in Figure 2, that is to say, so that it extends through all the vents J² in the

exhaust pipes J^1 and into engagement with the fixed contact H , the circuit being established from the cylindrical metallic member F , constituting one pole X of the circuit-breaker, and through the movable and fixed contacts F^4 , H to the dome or head H^1 constituting the second pole Y .

When the circuit-breaker is to be opened, the blast valve B^3 is opened by energising the opening solenoid S^1 so that the initial or filling pressure within the enclosure G is supplemented and the contact position F^3 is moved downwards into its cylinder F^2 . As the movable contact F^4 is withdrawn from the vents J^2 in the lateral exhaust pipes J^1 the exhaust valves J^3 are automatically opened by the gas pressure and a blast of deionising gas is caused to flow through each vent J^2 . After a predetermined interval, the blast valve B^3 is closed and the pressure within the enclosure G reverts to the initial or filling valve whereupon the exhaust valves J^3 close due to the pressure drop.

For closing the circuit-breaker, the relief valve B^4 in the base B of the circuit-breaker is opened so as to release the pressure within the enclosure G , the excess pressure on the lower face of the vented contact piston F^3 then moving the piston and movable contact F^4 upwards into the closed position. Having reclosed the relief valve B^4 , the pressure within the enclosure G automatically returns to the initial or filling value.

For very high voltages it may prove practicable to provide only a closed reception space or expansion chamber for the exhaust gases, the pressure in the said reception space being relieved through a single valve at a predetermined interval after the circuit-breaker has been opened. In the arrangement shown in Figure 3, which may either be provided with an automatically operated exhaust valve as in the construction first described above or with a valve for evacuating the gases from a reception space, the axially movable contact rod F^4 carries a piston F^3 movable within a cylinder F^2 under the gas pressure within the enclosure G^4 . The contact enclosure G^4 comprises two coaxial insulating cylinders G^5 , G^6 disposed one within the other and radially spaced apart, with the annular space G^7 between them in open communication with the pneumatic cylinder F^2 , as in the second arrangement described above. In the closed condition of the circuit-breaker the movable contact rod F^4 extends through or across a plurality of vents or nozzles K constituting the mouths of expansion chambers K^1 , K^2 , K^3 disposed within the enclosure G^4 . When the circuit-breaker is opened by supplementing the gas pressure within the enclosure G^4 , the movable contact F^4 is withdrawn from, so as to open, the vents or nozzles K and blasts of gas flow therethrough to assist in extinguishing the arc.

In the construction shown in Figure 4, the reception or expansion chamber and the enclosure together constitute a self-contained and enclosed gas circuit. The movable contact L moves relatively to the fixed contact rod M in a direction transverse to the axis of the associated nozzle N , as in the construction first described above, the cylinder L^1 of the contact piston L^2 , on that side thereof remote from the enclosure, being in open communication through a bleed passage L^3 with a reception chamber N^1 on the low pressure side of the nozzle N . The contact enclosure O on the high pressure side of the nozzle N is in open communication with a reservoir P formed in the base of the circuit-breaker, and pressure-control pistons Q are movable in a cylinder Q^1

whose upper and lower ends are respectively in open communications with the reception chamber N^1 on the low pressure side of the nozzle N and the contact enclosure O on the high pressure side of the nozzle N . The rod Q^2 of the pressure-control pistons Q carries at its lower end an actuating piston P^1 movable in a cylinder P^2 disposed within the reservoir P and having an associated "closing" valve P^3 and "opening" valve P^4 .

- 10 When the circuit-breaker is in the closed condition, the pressure-control pistons Q are in their uppermost positions and the gas pressure, throughout the gas circuit, including the reservoir P , contact enclosure O and reception chamber N^1 , is at the initial or filling value, i. e. the pressure within the reservoir P . To open the circuit-breaker, the opening valve P^4 is operated so that the pressure-control pistons Q move downwards and thus apply pressure to the gas in the enclosure O whilst at the same time reducing the pressure in the reception chamber N^1 . The increased pressure in the contact enclosure O assisted by the reduced pressure in the reception chamber N^1 moves the contact piston L^2 , and therefore the moving contact L , outwards away from the fixed contact M . The increased gas pressure on the high pressure side of the nozzle N accompanied by the simultaneous reduction in pressure on the low pressure side of the nozzle provides the necessary gas blast through the nozzle N for extinguishing the arc.

- For closing the circuit-breaker, the closing valve P^3 is operated so that the pressure-control pistons Q move upwards, thereby decreasing the pressure within the enclosure O so that the movable contact piston L^2 , assisted now by the increased pressure in the reception chamber N^1 , moves into engagement with the fixed contact rod M . The pressure then equalises throughout the system at the initial or filling value.

- 45 By suitably proportioning the gas spaces on the high and low pressure sides of the nozzle N respectively, a normally maintained initial or filling gas pressure of, say, four atmospheres can be converted, by operation of the pressure control piston Q , to a pressure of eight atmospheres on the high pressure side of the nozzle N and a pressure of one atmosphere on the low pressure side, thereby producing an adequate gas blast through the nozzle N during opening of the circuit-breaker.

- When the exhaust valve is live, as in known superatmospheric-filled open-type circuit-breakers, the valve has to be operated by some form of non-conducting mechanical coupling or independent pneumatic means. The invention, however, permits operation of the exhaust valve without such independent operating means. Further, since the gap between the open contacts lies in an atmosphere of gas at a pressure not less than the superatmospheric filling pressure throughout the opening movement and while the circuit-breaker remains open, the said gap can be reduced to a value which, while short enough to satisfy requirements of arc extinction, is yet sufficiently long to meet requirements of isolation without the provision of additional series-break isolating means, since, for usual gap configuration, the curve of dielectric break-down strength plotted against air-pressure rises steeply at its origin. In the latter respect, the initial or filling gas pressure maintained in the contact enclosure while the contacts are open need not exceed that necessary to ensure that a normal gap will withstand full voltage. For example,

the initial pressure may be about one third of that to which the gas pressure is raised during arc quenching.

What I claim as my invention and desire to secure by Letters Patent is:

1. A gas-blast electric circuit-breaker comprising an arcing enclosure, a restricted nozzle leading from such enclosure, two relatively movable cooperating contacts adjacent to the nozzle within the enclosure, means whereby the enclosure is maintained filled with gas under a superatmospheric initial or filling pressure, means whereby a blast of deionising gas is caused to flow from the enclosure past the contacts and through the nozzle in timed relation with the separating movement thereof so as to assist in extinguishing the arc drawn between the separating contacts, and means whereby the pressure within the enclosure is reinforced during the flow of the said blast thereby preventing reduction of the pressure within the enclosure below the said initial or filling value.

2. A gas-blast electric circuit-breaker comprising an arcing enclosure, a restricted nozzle leading from such enclosure, means whereby the enclosure is maintained filled with gas at a superatmospheric initial or filling pressure, two cooperating contacts adjacent to the nozzle within the enclosure, at least one of said contacts being movable, a cylinder, a piston within the cylinder and operatively connected to the movable contact, said piston being exposed to the gas pressure within the enclosure, and means whereby the gas pressure within the enclosure is supplemented so as to move said piston and separate the contacts whilst at the same time causing a blast of deionising gas to flow from the enclosure past the separating contacts and through the nozzle to assist in extinguishing the arc drawn between them, the said supplementation of the pressure preventing reduction of the pressure within the enclosure below the initial or filling value during the flow of the said blast.

3. A gas-blast electric circuit-breaker comprising an arcing enclosure having a restricted discharge nozzle or vent, two cooperating contacts within the enclosure on the high pressure side of the vent, at least one of said contacts being movable, an exhaust valve opening to atmosphere on the low pressure side of the vent, means whereby the enclosure is maintained filled with gas at a superatmospheric initial or filling pressure, means whereby the exhaust valve is opened to cause a blast of deionising gas to flow from the enclosure and past the contacts through the nozzle, and means whereby the gas pressure within the enclosure is reinforced during the flow of the blast thereby preventing reduction of the pressure within the enclosure to a value less than the initial or filling pressure.

4. A gas-blast electric circuit-breaker comprising an arcing enclosure, an exhaust valve controlling the discharge of gas from the enclosure, two relatively movable cooperating contacts within the enclosure, means whereby the exhaust valve and the contacts are opened in timed relation, means whereby gas under pressure is supplied to the enclosure so as to maintain the enclosure filled with gas under a superatmospheric initial or filling pressure while the exhaust valve is in the closed position, and means whereby the supply of gas under pressure to the enclosure is supplemented when the exhaust valve is opened, so that, though opening of the exhaust valve causes a blast of deionising gas to flow from the

enclosure and past the separating contacts to assist in extinguishing the arc drawn between them, reduction of the gas pressure within the enclosure below the initial or filling value is prevented by the supplementary gas supply.

5. A gas-blast electric circuit-breaker comprising an arcing enclosure, an exhaust valve controlling the discharge of gas from the enclosure, two relatively movable cooperating contacts within the enclosure, means whereby gas under pressure is supplied to the enclosure so as to maintain the enclosure filled with gas under a superatmospheric initial or filling pressure while the exhaust valve is in the closed position, means whereby the exhaust valve and the contacts are opened in timed relation by a gas pressure within the enclosure above the said initial or filling value, and means whereby the supply of gas to the enclosure is supplemented to open the exhaust valve and the contacts so that, though opening of the exhaust valve causes a blast of deionising gas to flow from the enclosure and past the separating contacts so as to assist in extinguishing the arc drawn between them, reduction of the gas pressure within the enclosure below the initial or filling value is prevented by the supplementary gas supply.

6. A gas-blast electric circuit-breaker comprising an arcing enclosure, an exhaust valve controlling the discharge of gas from the enclosure, two relatively movable cooperating contacts within the enclosure, means whereby gas under pressure is supplied to the enclosure so as to maintain the enclosure filled with gas under a superatmospheric initial or filling pressure while the exhaust valve is in the closed position, means whereby the exhaust valve and the contacts are opened in timed relation by a gas pressure within the enclosure above the said initial or filling value, means whereby the supply of gas to the enclosure is supplemented to open the contacts and exhaust valve, so that though opening of the exhaust valve causes a blast of deionising gas to flow from the enclosure and past the separating contacts so as to assist in extinguishing the arc drawn between them, reduction of the gas pressure within the enclosure below the initial or filling value is prevented by the supplementary gas supply, and a relief valve which, when opened, releases the pressure within the enclosure thus closing the exhaust valve and the contacts.

7. A gas-blast electric circuit-breaker comprising an arcing enclosure having a restricted discharge nozzle or vent, an exhaust valve on the low pressure side of the vent and controlling the discharge of gas from the enclosure through the vent, a valve-control chamber the pressure in which operates the exhaust valve, a bleed conduit interconnecting said chamber and the enclosure on the high pressure side of the vent, two cooperating contacts within the enclosure, at least one of said contacts being movable, a cylinder in open communication with the enclosure, a vented piston movable within the cylinder and operatively connected to the movable contact, means whereby gas under pressure is supplied to the enclosure so as to maintain the enclosure filled with gas under a superatmospheric initial or filling pressure while the exhaust valve is in the closed position, the gas pressure within the enclosure necessary to operate the exhaust valve and piston exceeding the said initial or filling pressure, and means whereby, when the circuit-breaker is to be opened, the

supply of gas under pressure to the enclosure is supplemented to raise the pressure therein to a value exceeding the initial or filling pressure thereby opening the exhaust valve and operating the piston to separate the contacts, so that though opening of the exhaust valve causes a blast of deionising gas to flow from the enclosure past the separating contacts and through the vent so as to assist in extinguishing the arc drawn between the contacts, reduction of the gas pressure within the enclosure below the initial or filling value is prevented by the supplementary gas supply.

8. A gas-blast electric circuit-breaker comprising an arcing enclosure having a restricted discharge nozzle or vent, an exhaust valve on the low pressure side of the vent and controlling the discharge of gas from the enclosure through the vent, a valve-control chamber the pressure in which operates the exhaust valve, a bleed conduit interconnecting said chamber and the enclosure on the high pressure side of the vent, two cooperating contacts within the enclosure, at least one of said contacts being movable a cylinder in open communication with the enclosure, a piston movable within the cylinder and operatively connected to the movable contact, means whereby gas under pressure is supplied to the enclosure so as to maintain the enclosure filled with gas under a superatmospheric initial or filling pressure while the exhaust valve is in the closed position, the gas pressure within the enclosure necessary to operate the exhaust valve and piston exceeding the initial or filling pressure, means whereby, when the circuit-breaker is to be opened, the supply of gas under pressure within the enclosure is supplemented to raise the pressure therein to a value exceeding the initial or filling pressure thereby opening the exhaust valve and operating the piston to separate the contacts, so that though opening of the exhaust valve causes a blast of deionising gas to flow from the enclosure past the separating contacts and through the vent so as to assist in extinguishing the arc drawn between the contacts, reduction of the gas pressure within the enclosure below the initial or filling value is prevented by the supplementary gas supply, and a relief valve which, when opened, releases the pressure within the enclosure thus causing the exhaust valve and movable contact to reclose.

9. A gas-blast electric circuit-breaker comprising an arcing enclosure, an exhaust valve controlling the discharge of gas from the enclosure, two relatively movable cooperating contacts within the enclosure, means whereby the exhaust valve and contacts are opened in timed relation, a reservoir containing gas under superatmospheric pressure, a primary gas supply conduit connecting the reservoir to the enclosure, a reducing valve determining the supply of gas through the primary conduit to the enclosure which is thus maintained filled with gas at a superatmospheric initial or filling pressure, as determined by the reducing valve, while the exhaust valve is in the closed position, a supplementary gas supply conduit connecting the reservoir to the enclosure, and a blast valve controlling said supplementary conduit, the blast valve being opened when the exhaust valve is opened so that, though opening of the exhaust valve causes a blast of deionising gas to flow from the enclosure and past the separating contacts to assist in extinguishing the arc drawn between them, reduction of the gas pressure within the

enclosure below the initial or filling value is prevented by the supplementary gas supply.

10. A gas-blast electric circuit-breaker as claimed in claim 9, in which the exhaust valve and the contacts are opened by a gas pressure within the enclosure exceeding the initial or filling pressure, so that the said valve and contacts are opened by opening the blast valve.

11. A gas-blast electric circuit-breaker as claimed in claim 9, in which the exhaust valve and contacts are opened by a gas pressure within the enclosure exceeding the initial or filling pressure, so that the said valve and contacts are opened by opening the blast valve, and a relief valve is provided which, when opened, releases the gas pressure within the enclosure and thus causes the exhaust valve and contacts to reclose.

12. A gas-blast electric circuit-breaker comprising an arcing enclosure having a restricted discharge nozzle or vent, an exhaust valve on the low pressure side of the vent and controlling the discharge of gas from the enclosure through the vent, a valve-control chamber the pressure in which operates the exhaust valve, a bleed conduit interconnecting said chamber and the enclosure on the high pressure side of the vent, two cooperating contacts within the enclosure, at least one of said contacts being movable, a cylinder in open communication with the enclosure on the high pressure side of the vent, a vented piston movable within said cylinder and operatively connected to the movable contact, a reservoir containing gas under superatmospheric pressure, a primary gas supply conduit connecting the reservoir to the enclosure, a reducing valve determining the supply of gas through the primary conduit to the enclosure which is thus maintained filled with gas at a superatmospheric initial or filling pressure, as determined by the reducing valve, while the exhaust valve is in the closed position, a supplementary gas supply conduit connecting the reservoir to the enclosure, a blast valve controlling the supply of gas through the supplementary conduit, and a relief valve which, when opened, relieves the pressure within the enclosure and thus causes the exhaust valve and contacts to reclose, so that when the circuit-breaker is to be opened, the blast valve is opened whereby the exhaust valve and the movable contact are moved into their open positions and, though a blast of deionising gas is thus caused to flow from the enclosure and past the separating contacts to the vent, thus assisting in extinguishing the arc drawn between the contacts, reduction of the pressure within the enclosure to a value below the initial or filling pressure is prevented by the supplementary gas supply, and when the circuit-breaker is to be closed, the relief valve is opened so that the exhaust valve and the movable contact are restored to their closed positions.

13. A gas-blast electric circuit-breaker comprising an arcing enclosure having at least one discharge nozzle or vent, a gas-expansion chamber communicating with said vent, two cooperating contacts within the enclosure, at least one of said contacts being movable and, when in its closed position, extending into, so as to close, the vent, a cylinder, a vented piston operatively connected to the movable contact and slideable within said cylinder which is in open communication with the enclosure through the vent in the piston, means whereby gas under pressure is supplied to the enclosure so that the enclosure

is maintained filled with gas at a superatmospheric initial or filling pressure, and means whereby the supply of gas under pressure to the enclosure can be supplemented, thereby operating the piston and withdrawing the movable contact from the vent so that, though a blast of deionising gas is thus caused to flow through the vent and past the separating contacts to the expansion chamber, thus assisting in extinguishing the arc drawn between them, reduction of the pressure within the enclosure below the initial or filling value is prevented by the supplementary gas supply.

14. A gas-blast circuit-breaker as claimed in claim 13, in which the discharge of gas from the gas-expansion chamber is controlled by a spring-loaded exhaust valve.

15. A gas-blast electric circuit-breaker as claimed in claim 13, having a relief valve which, when opened, relieves the pressure within the enclosure so that the pressure within the cylinder predominates and restores the movable contact to its closed position.

16. A gas-blast electric circuit-breaker comprising an arcing enclosure having at least one discharge nozzle or vent, a gas-expansion chamber communicating with said vent, two cooperating contacts within the enclosure, at least one of said contacts being movable and, when in its closed position, extending into, so as to close, the vent, a cylinder, a vented piston operatively connected to the movable contact and slidable within said cylinder which is in open communication with the enclosure through the vent in the piston, a reservoir filled with gas under superatmospheric pressure, a primary gas-supply conduit connecting the reservoir to the enclosure, a reducing valve determining the supply of gas through the primary conduit to the enclosure, so that the enclosure is maintained filled with gas at a superatmospheric initial or filling pressure, a supplementary gas supply conduit connecting the reservoir to the enclosure, and a blast valve controlling the supply of gas under pressure through the supplementary conduit to the enclosure, opening of the blast valve causing the gas pressure within the enclosure to be supplemented whereby the piston is operated to withdraw the movable contact from the vent so that, though a blast of deionising gas is thus caused to flow from the enclosure, past the separating contacts and through the vent to the expansion chamber, thereby assisting in extinguishing the arc drawn between the contacts, reduction of the pressure within the enclosure to a value below the initial or filling pressure is prevented by the supplementary gas supply.

17. A gas-blast circuit-breaker as claimed in claim 16, having a relief valve which, when opened, relieves the pressure within the enclosure so that the pressure within the cylinder predominates and restores the movable contact to its closed position.

18. A gas-blast electric circuit-breaker comprising an arcing enclosure having at least one discharge nozzle or vent, a gas-expansion chamber communicating with said vent, two cooperating contacts within the enclosure, at least one of said contacts being movable and, when in its closed position, extending into, so as to close, the vent, a cylinder, a vented piston operatively connected to the movable contact and slidable within said cylinder which is in open communication with the enclosure through the vent in the piston, an exhaust valve controlling the dis-

charge of gas from the enclosure, a valve-control chamber the pressure in which operates the exhaust valve, a bleed conduit communicating between the enclosure and said valve-control chamber, means whereby gas under pressure is supplied to the enclosure so that the enclosure is maintained filled with gas at a superatmospheric initial or filling pressure, and means whereby the supply of gas under pressure to the enclosure can

5 be supplemented, thereby operating the piston to withdraw the movable contact from the vent so that, though a blast of deionising gas is thus caused to flow through the vent and past the co-operating contacts to the expansion chamber and past the exhaust valve, thus assisting in extinguishing the arc drawn between the contacts, reduction of the pressure within the enclosure below the initial or filling value is prevented by the supplementary gas supply.

19. A gas-blast electric circuit-breaker as claimed in claim 18, having a relief valve which, when opened, relieves the pressure within the enclosure so that the pressure within the cylinder predominates and restores the movable contact to its closed position.

20. A gas-blast electric circuit-breaker comprising an arcing enclosure having at least one discharge nozzle or vent, a gas expansion chamber communicating with said vent, two cooperating contacts within the enclosure, at least one of said contacts being movable and, when in its closed position, extending into, so as to close, the vent, a cylinder, a vented piston operatively connected to the movable contact and slidable within said cylinder, an exhaust valve controlling the discharge of gas from the enclosure and expansion chamber, a valve-control chamber the pressure in which operates the exhaust valve, a bleed passage communicating between the said chamber and the enclosure, a reservoir filled with gas under superatmospheric pressure, a primary gas-supply conduit connecting the reservoir to the enclosure, a reducing valve determining the supply of gas through the primary conduit to the enclosure, so that the enclosure is maintained filled with gas at a superatmospheric initial or filling pressure, a supplementary gas-supply conduit connecting the reservoir to the enclosure, and a blast valve controlling the supply of gas under pressure through the supplementary conduit to the enclosure, opening of the blast valve causing the gas pressure within the enclosure to be supplemented whereby the piston is operated to withdraw the movable contact from the vent so that, though a blast of deionising gas is caused to flow from the enclosure, past the separating contacts and past the exhaust valve from the vent and expansion chamber, thereby assisting in extinguishing the arc drawn between the contacts, reduction of the pressure within the enclosure to a value below the initial or filling pressure is prevented by the supplementary gas supply.

21. A gas-blast electric circuit-breaker as claimed in claim 20, having a relief valve which, when opened, relieves the pressure within the cylinder predominates to restore the movable contact to its closed position, the predominating atmospheric pressure at the same time predominating over that in the valve-control chamber to restore the exhaust valve to its closed position.

22. A gas-blast electric circuit-breaker comprising an arcing enclosure having a discharge vent or nozzle, an expansion chamber communi-

cating with the low pressure side of the nozzle, a pressure chamber communicating with the enclosure on the high pressure side of the nozzle, two cooperating contacts within the enclosure on the high pressure side of the nozzle, at least one of said contacts being movable under the gas pressure within the enclosure, a cylinder communicating at opposite ends respectively with the expansion chamber and pressure chamber, a piston slidale within said cylinder, means whereby the enclosure is maintained filled with gas under a superatmospheric initial or filling pressure, means whereby the piston is operated in one direction to supplement the pressure in the enclosure and reduce the pressure in the expansion chamber thus moving the movable contact towards the open position and causing a blast of deionising gas to flow from the enclosure and past the separating contacts to the nozzle, thereby assisting in extinguishing the arc drawn between the contacts whilst preventing reduction of the gas pressure within the enclosure below the initial or filling pressure, and means whereby the piston is operated in the reverse direction to reduce the pressure in the enclosure thereby restoring the movable contact to the closed position.

15

23. A gas-blast circuit-breaker as claimed in claim 22, in which the enclosure and the cylinder are in permanent open communication with a reservoir containing gas under the initial or filling gas pressure.

24. A gas-blast circuit-breaker as claimed in claim 22, in which the movable contact is operatively connected to a piston movable in a cylinder one end of which is in open communication with the arcing enclosure on the high pressure side of the nozzle whilst the other end of the cylinder is in open communication with the expansion chamber on the low pressure side of the nozzle.
